UNITED STATES PATENT OFFICE.

EDWARD CHRISTIAN HORN AND FULLER CLAFLIN, OF NEW YORK, N. Y.

WATER-HEATER.

SPECIFICATION forming part of Letters Patent No. 613,372, dated November 1, 1898.

Application filed April 26, 1897. Serial No. 633,998. (No model.)

To all whom it may concern:

Be it known that we, EDWARD CHRISTIAN HORN and FULLER CLAFLIN, of the city, county, and State of New York, have invented 5 certain new and useful Improvements in Water-Heaters, of which the following is a specification.

The object of our invention is to instantaneously heat a continuous stream of water by 10 means of a gas-burner and its connections.

In the accompanying drawings, which embody our invention, Figure 1 is a vertical section of the device. Fig. 2 is a side view of same. Fig. 3 is a top plan of the gas-burner 15 and connections at point indicated by dotted lines α α in Fig. 1. Fig. 4 is a bottom plan of the device with supply and outlet pipes removed. Fig. 5 is a bottom plan of the reservoir through which water is supplied to the 20 heating combination.

Referring more particularly to the drawings, A indicates a cylinder slightly enlarged at each end, inside of which is the gas-burner B, supplied with gas by the pipe C.

D indicates a reservoir supplied with water 25 from the pipe E, which is screwed into a hole in the top of the reservoir. This pipe may be unscrewed from the reservoir and the funnel F substituted, water being then poured into 30 the funnel.

G indicates rods passing downward through slightly-larger holes G' in the bottom of the reservoir.

H indicates shorter lengths of rods passing 35 similarly downward through the holes H' and kept in position from working upward by the collar I, which rests loosely on the inside bottom of the reservoir.

The rods G are held in position at their 40 lower ends by the circular flat plate J, through which they pass, and a small nut K on the bottom end of two rods keeps the plate from dropping when the reservoir and rods are lifted out of the cylinder for cleaning purposes.

The burner B is in the form of a cone and, as indicated by the drawings, has four openings in the sides near the top and a smaller round opening on the extreme top, at which 45 points the gas is ignited. A fixed circular plate L forms the bottom of the burner and also a bottom inside the cylinder. In this

plate is a center hole through which the end of the pipe C passes and also two openings M. (Indicated by dotted lines in Fig. 4.) Beneath 55 this plate is a movable circular plate N, with a similar center hole and similar openings O, and to this plate is attached a lever P, which passes outside of the cylinder through the slot Q. By pushing this lever from the position in which it is shown by solid lines P in Fig. 4 to the position shown by dotted lines P' the openings in the plate N coincide with the openings in the plate L, admitting air to the bottom of the burner, which air is mixed 60 with the gas supplied by the pipe C and controlled as to amount admitted by adjustment of the lever.

R indicates openings in the cylinder, through which air is admitted, and S a similar opening through which to light the gas as it emerges from the burner.

T indicates a pipe through which the heated water flows from the device.

It is evident that when the reservoir D is 75 filled with water small streams will run from its bottom through the holes G' and H' and down the rods G and H, which are enough smaller than the holes to not entirely fill them, and it is also evident that from the ends of 80 the rods H, which, owing to the beveled bottom edge of the reservoir D, are inclined toward the side of the cylinder A, the water will run onto and down the inside of the cylinder, while from the longer rods G the water will 85 drip to the inside bottom of the cylinder, whence, uniting with the water which has run down the inside of the cylinder, it will emerge from the device through the pipe T. It is further evident that the combustion of gas 90 and air at the top of the burner B will heat the water thus conveyed and distributed to and around the burner.

We are aware that it is not new to provide a gas-burning water-heater with a cylindrical 95 hot-air flue through which pass wires for the distribution and heating of water fed to the wires from a reservoir above same, and such we do not claim, broadly, as our invention.

What we claim as new, and desire to secure 100 by Letters Patent, is—

1. In a water-heater, an outer shell, provided with a heating device located near its bottom and a reservoir for receiving and dis-

tributing water located near its top, in combination with a series of straight, round, metal rods, G, entering said reservoir vertically through a corresponding series of holes 5 in its bottom, and extending downwardly therefrom and through a corresponding series of holes in an annular plate located near the bottom of said shell, beneath which said plate the said rods terminate, and through the center of which said plate the said heating device protrudes upwardly, the said rods being adapted to distribute and convey small streams of water from said reservoir to and around said heating device, substantially as 15 shown and described.

2. In a water-heater, an outer shell, provided with a heating device located near its bottom and a reservoir for receiving and distributing water located near its top, and a 20 series of straight, round, metal rods entering said reservoir vertically through a corresponding series of holes in its bottom and extending downwardly therefrom and through a corresponding series of holes in an annular 25 plate located near the bottom of said shell, beneath which said plate the said rods terminate, and through the center of which said plate the said heating device protrudes upwardly, in combination with a second series 30 of straight, round, metal rods, H, entering said reservoir obliquely through a corresponding series of holes near the edge of its bottom, and extending outwardly and downwardly therefrom, terminating against the inner sur-

face of said outer shell; the said second series 35 of rods being adapted to distribute and convey water from said reservoir to and around the inner surface of said outer shell, substantially as shown and described.

3. In a water-heater, an outer shell, provided with a heating device located near its bottom and a reservoir for receiving and distributing water located near its top, and a 40 series of straight, round, metal rods entering said reservoir vertically through a corresponding series of holes in its bottom and extending downwardly therefrom and through a corresponding series of holes in an annular plate located near the bottom of said shell, beneath which said plate the said rods terminate, and through the center of which said 45 plate the said heating device protrudes upwardly, and a second series of straight, round, metal rods entering said reservoir obliquely through a corresponding series of holes near 50 the edge of its bottom and extending outwardly and downwardly therefrom, terminating against the inner surface of said outer shell, in combination with a cylindrical collar, I, inside of said reservoir, said collar being 55 adapted to keep said second series of rods from sliding upwardly, substantially as shown and described.

EDWARD CHRISTIAN HORN.
FULLER CLAFLIN.
